T. M. Seiden-Decker

UNITED STATES PATENT OFFICE.

MAURICE LACHMAN, OF NEW YORK, N. Y.

METAL POLE, GIRDER, OR BEAM.

1,382,199.

Specification of Letters Patent. Patented June 21, 1921.

Application filed April 22, 1920. Serial No. 375,656.

To all whom it may concern:

Be it known that I, MAURICE LACHMAN, a citizen of the United States, and a resident of New York, in the county of New York and State of New York, have invented certain new and useful Improvements in Metal Poles, Girders, or Beams, of which the following is a specification.

My present invention relates to such structures as hollow metal poles, beams, box girders and the like and the object is to provide a box pole or girder construction which requires the handling of but few parts and which can be formed of standard rolled sections having great strength.

A further object is to substitute press-work for the usual fabrication, thereby quickening and simplifying the process of manufacture and naturally resulting in lowered cost.

The invention consists in the improved construction of metal pole, girder, beam or the like as hereinafter more particularly described and then specified in the claims.

25 In the accompanying drawings, Figure 1 is an end view of a rolled section of standard shape which is preferably used in carrying out this invention.

Fig. 2 is a plan of the same, showing the 30 cuts subdividing the web.

Fig. 3 is a transverse cross-section taken on the line 3—3 Fig. 2 and shows the structure after the parts have been bent or formed into finished shape.

35 Fig. 4 is a side elevation of a portion of the finished pole or beam, the tying members being shown in section.

As to the main element of the pole, girder or beam I employ a rolled section having 40 longitudinally flanged edges and by preference use a standard I-beam of a size suitable for the size pole or beam desired. In the drawings, 1 indicates the web of such a beam and 2 the flanges running along the longitudinal edges; which flanges, when an I-beam is employed, run in both directions from the web 1.

The web, as indicated in Fig. 2, is subdivided transversely into a plurality of portions or parts by cuts 3 which preferably run diagonally from one flanged edge 2 to the central line of the web and then diagonally in the opposite direction to the other flanged edge of the section.

55 This cutting or subdividing may be done in a press or in any other desired manner

and results in the formation of a number of portions separated from each other except at the flanged edges 2.

By subdividing the web as shown alternate portions 4 are duplicates of each other and alternate portions 5 are duplicates of each other.

After subdivision, the section is run through a suitable press, or by any other forming operation, the alternate portions 4 and the alternate portions 5 are bent transversely to the normal plane of the web. The parts 4 are all bent or expanded in the one direction and the parts 5 are all bent in the opposite direction, the bending being preferably continued until the structure has a hollow box-like appearance with square or flat sides as indicated in Fig. 3.

6 indicates longitudinal members, preferably angle or L-shaped, which engage the outer free ends of both sets of outwardly bent portions 4 and 5. These members preferably engage the outermost part of the portions 4 and 5 and are riveted or welded to 80 such portions to secure and effectively tie the portions to each other.

In this manner a hollow trussed pole or girder is obtained without any fabrication whatever except the securing of the tie members 6.

If desired to simulate a latticed pole or if desired to lighten the structure parts of the portions 4 and 5 may be removed as indicated by the dotted lines 7 in Fig. 2.

90 What I claim as my invention is:

1. A metal pole or beam comprising a rolled section having flanged edges, the web of said section being divided into a plurality of portions bent alternately in opposite directions out of the normal plane of the web and members tying the projecting edges of said portions together.

2. A metal pole or beam comprising a rolled section having longitudinally flanged edges, the web of said section being divided transversely into a plurality of portions bent alternately out of the normal plane of the web to form a hollow box-like structure and members engaging and tying together the 105 free ends of the bent out portions.

3. A metal pole or beam comprising a rolled section having longitudinally flanged edges, the web of said section being divided on diagonal lines into a plurality of portions, alternate portions being duplicates of each other and bent alternately in opposite

- directions from the normal plane of the web and longitudinal members tying the free ends of said outwardly bent portions together.
5. A metal pole or beam comprising a rolled section having longitudinally flanged edges, the web of said section being divided, by cuts running diagonally from one flanged edge to the center line of the web and then 20 diagonally but in the opposite direction to the other flanged edge, into a plurality of portions integral with the flanged edges, said portions being bent alternately in opposite directions from the normal plane of 25 the web and members tying the outer edges of said outwardly bent portions together.
5. A metal pole or post comprising a rolled section having longitudinal flanged edges, the web of said section being divided into a plurality of diamond shaped parts, alternate parts being duplicates of each other, said parts being bent alternately out of the normal plane of the web to form a box-like structure and members secured to and tying said parts together at their outwardly bent portions.

Signed at New York in the county of New York and State of New York this 16th day of April, A. D. 1920.

MAURICE LACHMAN.

Witness:

IRENE LEFKOWITZ.
